U.S. Appl. No. 29/360,868, filed Apr. 30, 2010.

(Continued)

Primary Examiner — Marianne Pandozzi(74) *Attorney, Agent, or Firm* — Baker Botts L.L.P.(57) **CLAIM**

The ornamental design for a sidewall for a cup, as shown and described.

DESCRIPTION

FIG. 1 is a top perspective view of a sidewall for a cup showing our new design;

FIG. 2 is a side view of the sidewall for a cup of FIG. 1; FIG. 3 is a top view of the sidewall for a cup of FIG. 1; and, FIG. 4 is a bottom view of the sidewall for a cup of FIG. 1. The broken lines shown throughout these figures depict environmental subject matter only and form no part of the claimed design.
